SAFETY RAZOR

Angus A. Martin, Dorchester, and Richard E.
Johnston, Boston, Mass.

Application October 20, 1933, Serial No. 694,474

5 Claims. (Cl. 30—12)

This invention relates to safety razors and it consists in the novel features, hereinafter described and claimed.

In general, the invention may apply to a complete safety razor including a blade and blade holding device, but the primary object of the invention is to provide a blade holder and handle of simple, inexpensive and practical design to meet all requirements and adapted to the use of the many types of safety razor blades now on the market. The razor blades may be slotted or cut out at their centers, or the said blades may be solid.

With the above object in view, the safety razor includes a bed plate provided at its ends with flanges adapted to engage the end edges of the razor blade so that the said blade cannot move longitudinally, there being slot and lug engagement between the razor blade and the flanges to prevent relative transverse movement of the blade. The invention further contemplates the provision of a guard member pivoted between the flanges and having teeth adapted to bear against the side of the blade when the guard member is swung or turned whereby the blade is firmly clamped in position against the bed plate, and is curved slightly so that the cutting edge of the blade will be properly presented to the hair during the use of the razor. Handle sections are provided for swinging the guard member and for supporting the holder, and securing devices are provided upon the handle sections for temporarily fixing the same with relation to each other to form a complete handle, which may be used for manipulating the razor over the surface bearing the hair.

With the foregoing objects in view, the invention is included in two forms in one of which a plurality of guard members is used, and a double edged blade is employed. In the other form, a single guard member is used and the blade is provided with but a single cutting edge.

In the accompanying drawing:

Fig. 1 is a perspective view of one form of the safety razor wherein a double edged blade is used and a plurality of guard members employed.

Fig. 2 is a perspective view of the safety razor showing the parts in open position, and the blade removed from the holder.

Fig. 3 is a longitudinal sectional view of the safety razor showing the handle members thereof closed together.

Fig. 4 is a fragmentary longitudinal sectional view of the safety razor showing the handle members at open position.

Fig. 5 is a perspective view of another form of the safety razor.

Fig. 6 is a fragmentary sectional view of the form of razor as shown in Fig. 5, and showing the handle members closed.

Fig. 7 is a fragmentary sectional view of the form of safety razor as shown in Fig. 5 and showing the handle members at open position.

Fig. 8 is a transverse sectional view of the safety razor cut on the line 8—8 of Fig. 7.

Fig. 9 is an end view of the handle members of the safety razor as shown in Fig. 5 and illustrating one form of security device for temporarily connecting the handle members together.

In the form of the invention as illustrated in Figs. 1 to 4 inclusive, the safety razor comprises a bed plate 1 having upstanding flanges 2 at the ends thereof. The flanges at one side edge of the plate are spaced from the flanges at the opposite side edge to provide clearance space thru which the bristles and lather may pass during the act of shaving.

A guard member 3 is pivoted at its ends between the flanges 2 at the same side edge of the bed plate 1 and spaced teeth 4 are carried by the guard member. These teeth have pointed ends and they are adapted to swing about the axis of the guard member when the same is turned and serve as means for clamping the razor blade in position upon the bed plate as will be herein-after explained.

Handle sections 5 are attached to the guard members 3, and securing devices 6 are carried at the free ends of the handle sections 5 and serve to connect the said sections together to form a handle, as shown in Fig. 1 of the drawing.

A blade 7 is provided at its ends with lugs 8, which are adapted to fit between the flanges 2 at the opposite side edges of the guard plate. The blade is provided with the longitudinal slot 9 that it may readily flex or bend when encountered by the teeth 4, and thus the blade is securely held in position upon the plate. During the act of shaving, either of the two longitudinal edges of the blade may be used for shaving.

In the form of the invention, as illustrated in Figs. 5 to 9 inclusive, the razor consists of a bed plate 10, provided with a shank 11. Flanges 12 are struck up from the end edges of the bed plate 10 and a guard member 13 is pivoted between said flanges. Teeth 14 are carried by the guard member 13. Handle sections 15 are provided, and one of them is carried by the shank 11 and the other by the guard member 13.

Securing devices 16 are carried at the free ends

of the handle sections 15 and said securing devices are in the form of globular extensions adapted to overlap each other and frictionally engage each other, as shown in Fig. 5 of the drawing and 5 whereby the handle sections are temporarily secured together to form a handle.

The blade 17 is provided with but a single cutting edge and the said blade is provided at its ends with notches 19 adapted to receive lugs 18 10 turned inwardly from the inner ends of the flanges 12.

In both forms of the invention it will be seen that a bed plate having flanges at its ends is provided and that a razor blade fits between said 15 flanges and engages the same so that relative longitudinal and lateral movement of the blade is prevented, also a guard member is pivoted between the flanges and is provided with teeth adapted to engage the side of the blade and flex 20 the same whereby the blade is firmly clamped in position against the side of the bed plate.

Having described the invention, what is claimed is:

1. A safety razor comprising a bed plate provided at its ends with upstanding flanges, a blade adapted to rest upon the bed plate between the flanges, there being lug and slot engagement between the blade and flanges, a guard pivoted between the flanges and teeth carried by the guard 30 and adapted to engage the blade and flex the same in position against the bed plate.

2. A safety razor comprising a bed plate provided at its ends with upstanding flanges, a blade fitting between the flanges, means for holding the 35 blade against movement with relation to the flanges, guard members pivoted to the flanges and

having teeth adapted to engage the blade and flex the same and handle sections carried by the guard members.

3. A safety razor comprising a bed plate having flanges at the ends thereof, a blade adapted to engage said flanges, guard members pivoted between the flanges and having teeth adapted to engage the blade and clamp the same against the bed plate, handle sections carried by the guard members and securing devices for connecting the free ends of the handle sections together. 85

4. A safety razor comprising a bed plate provided at its corners with upstanding flanges, said flanges at the ends of the plates being spaced from each other to provide clearance space for the exit of lather, a blade resting upon the bed plate and engaging the edges of the flanges, guard members pivoted to the flanges and having teeth adapted to engage the blade and flex the same, and handle sections carried by the guard members. 90

5. A safety razor comprising a bed plate provided at its ends with flanges having inturned lug extremities, a blade adapted to rest upon the plate and having at its ends slots adapted to receive the lug extremities of the flanges, a handle section connected with the bed plate, a guard member pivoted between the flanges and having teeth adapted to engage the side of the blade and flex the same against the bed plate, a handle 105 section carried by the guard member and a securing device for temporarily connecting the handle sections together. 100
